UNITED STATES PATENT OFFICE.

MORRIS MARTIN, OF MALDEN, MASSACHUSETTS.

THERMOMETRIC ELECTRIC-CIRCUIT CLOSER.

SPECIFICATION forming part of Letters Patent No. 286,722, dated October 16, 1883.

Application filed January 29, 1883. (No model.)

To all whom it may concern:

Be it known that I, MORRIS MARTIN, of Malden, in the county of Middlesex, of the Commonwealth of Massachusetts, have invented a new and useful Improvement in Thermometric Electric-Circuit Closers; and I do hereby declare the same to be described in the following specification, and represented in the accompanying drawings, of which—

10. Figure 1 is a front elevation, and Fig. 2 a transverse section, of a thermometric electric-circuit closer embodying my invention, the nature of which is defined in the claims herein-after presented. Fig. 3 is a rear view, and 15 Fig. 4 a transverse section, of the dial and its stationary and revolute rings. Fig. 5 is a view of the thermometric mechanism contained in the case of the apparatus and for operating the dial-hand.

20. The object of the instrument shown in the drawings is to close an electro-galvanic circuit at any degree of temperature indicated on the dial, in order to cause the electro-magnet of such circuit to draw toward it its armature and such armature to operate some mechanism or apparatus connected with or applied to it.

25. In the drawings, A denotes a cylindrical box or case, provided with a metallic dial, B, which is a flat annulus, having upon its outer surface divisions and figures indicative of changes of temperature. Within and concentric with the dial is another flat metallic ring, C, which is revolute within the dial, and besides is 30 provided on its inner side with a metallic spring, D, to extend from it and lap upon another ring, E, arranged in rear of the dial and connected therewith by a series of insulators, a a a, of vulcanized rubber. The spring D is 35 electrically insulated from the revolute ring C by means of a block, e, of hard rubber placed between them and fixed to the ring and to such spring. Furthermore, there extends from the spring upward through and somewhat above 40 the ring C, but without being in contact with such ring, though electrically insulated from it, a metallic stud, b. Fixed in the ring C, close to the stud, and in a radial line extending through it from the center of the dial, is an 45 other metallic stud, c, they being arranged so that when the metallic hand F of the dial may be moved around in contact with either stud

such hand will also touch the other stud. One of the electrical circuit wires is shown at G as extending from the dial, and the other at H as 55 extending from the insulated ring E. The hand F is fixed on an arbor, f, that carries a pinion, g, which engages with a rack, h, adapted to slide lengthwise, the arbor and pinion being arranged in a bracket, k, extending 60 upward from a flat bar, l, screwed to the case. The said bar, near one end of it, is bent upward and has one extremity of a serpentine-shaped bar, m, of metal fixed to it. This bar goes loosely through a guide, n, and has a stud or pin, o, 65 extended from it into a long slot, p, in another bar, q, which, at its upper end, is jointed to the rack. The said bar q at its lower end is pivoted or hinged to a block, r, and into which is screwed an adjusting-screw, s, adapted to 70 the bar l, so as to be revolute transversely, but not movable longitudinally therein. The screw at its lower end is nicked to receive the end of the blade of a screw-driver, when extended into the case through a hole made there-in line with the screw. Any increase of 75 the temperature will cause the bar m to expand lengthwise, and thereby move the slotted bar q and cause it to move the rack lengthwise thereof, whereby the pinion will be revolved, so as to cause the hand to be moved 80 about the dial. If, when the two studs of the revolute ring are set to range with any given division of the scale indicative of the temperature at which it may be desirable to have the 85 circuit closed, and at such temperature the adjusting-screw s be revolved until the hand may be carried into contact with the two metallic studs, such hand, on the temperature falling, will, by consequent contraction of the bar 90 m, be moved away from the studs, and so long as the temperature of the surrounding air may be less than that at which the circuit is to be closed, the hand will remain out of contact 95 with the studs; but on the temperature rising to the necessary extent the metallic hand will be carried in contact with the two studs, and consequently the circuit will be closed. In order that the hand may be sure to make electrical contact with the studs, there is pivoted 100 at its middle, to the hand, a block or piece of metal, t, which will turn and be sure to touch both studs as the hand may move toward them, so as to carry the piece t into contact with

either of them, and may continue to advance. This piece or block may extend from one or each side of the hand.

I do not claim a thermometric dial-hand operative mechanism, as described in either of the United States Patents Nos. 89,757 and 251,359, as in neither of them are to be found a sliding block, an adjusting-screw, and a slotted arm adapted to the rack and spring as 10 in my invention.

What I claim is as follows:

1. The electric-circuit closer, substantially as described, consisting of the dial, the revoluble ring, and its insulated spring and their 15 two studs, and the insulated ring, all being to operate as explained, with the circuit-wires and with the dial-hand provided with mech-

anism for actuating it, substantially as described.

2. The thermometric dial-hand operative 20 mechanism, substantially as described, consisting of the pinion, rack, slotted bar, and its supporting-block and its adjusting-screw, and the expansible bar, arranged and adapted essentially in manner and to operate as set forth. 25

3. The combination of the vibratory metal- 25 lie block or piece *t*, with the dial-hand adapted to operate with the two electric-circuit-studs, arranged as set forth.

MORRIS MARTIN.
